Specification for Design.

Patented July 20, 1920.

Application filed April 23, 1919. Serial No. 292,176. Term of patent 3½ years.

To all whom it may concern:

Be it known that I, JULIUS B. MELTZ, a citizen of the United States of America, residing at Everett, in the county of Middlesex and Commonwealth of Massachusetts, have invented a new, original, and ornamental Design for an Ice-Cream Cone or Similar Article, of which the following is a specification, reference being had to the accompanying drawing, forming a part thereof.

In said drawing the figure is a perspective view of an ice cream cone showing my new design.

I claim:

The ornamental design for an ice cream cone or similar article, substantially as shown.

Signed by me at Boston, in the county of Suffolk and Commonwealth of Massachusetts, this 15th day of April, 1919.

JULIUS B. MELTZ.
